UNITED STATES PATENT OFFICE.

ROBERT J. HEWETT, OF WESTFIELD, NEW JERSEY, ASSIGNOR TO THE
HALL SIGNAL COMPANY, A CORPORATION OF MAINE.

ELECTRICAL DEVICE AND CIRCUIT.

No. 818,170.

Specification of Letters Patent.

Patented April 17, 1906.

Application filed June 2, 1905. Serial No. 263,501.

To all whom it may concern:

Be it known that I, ROBERT J. HEWETT, a citizen of the United States, and a resident of Westfield, county of Union, and State of New Jersey, have invented certain new and useful Improvements in Electrical Devices and Circuits, of which the following is a specification.

This invention relates to improvements in electrical devices and circuits, and more particularly to such as are adapted and designed for use in connection with electric signaling systems for railways.

The invention seeks to provide an arrangement whereby an economy of current consumption may be effected in operating a relay.

The invention is more particularly useful in connection with what is known as a "track-relay."

In track-signal work the term "track-relay" is generally applied to the relay located at the entering end of a track-section. It is energized or responsive when there is no train in the track-section and is deenergized or made unresponsive by the presence of a train in the track-section. It is used in connection with signals normally at "danger" and also in connection with signals normally at clear or safety position.

The term "clearing-relay" is generally applied to the relay located at the exit end of a track-section and is used in connection with signals normally at "danger." The clearing-relay is deenergized or unresponsive when there is no train in the track-section and is energized or made responsive by the presence of a train in the track-section.

The accompanying drawing, forming part of this specification, shows one block of a signaling system having the signal normally at "safety."

The track-relays associated with the system show the invention in three different forms.

Referring now more particularly to the drawing, 1, 2, and 3 are subsections of the track-section or block, having three stations A, B, and C. The signal 4, which guards the section or block, is normally at "safety."

The magnet 5, connected in circuit with the battery 6 and circuit-controller 7, represents the motor-controlling magnet for the signal. Magnet-coils 8 and 12 are the magnet-coils of the track-relay at station A.

9 and 10 are the lead-wires from subsection 1 to this relay. Magnet-coil 8 is connected on one side with wire 9 and is connected on its other side with wire 10 through movable contact 11. Magnet-coil 12 is connected on one side by wire 13 with wire 9, and is connected on its other side by wire 14 and movable contact 15 with wire 10. Movable contacts 11 and 15 constitute the circuit-changer. When this circuit-changer is in the position shown in the drawing, magnet-coil 8 is included in the track-circuit and magnet-coil 12 is excluded therefrom. When the circuit-changer is in its other position, magnet-coil 8 is excluded from the track-circuit and magnet-coil 12 is included in said circuit. In this latter position contact 11 will be open and contact 15 will be closed. The circuit-changer may be operated in any suitable manner. At station A it is shown as mechanically connected with and operated by the operating-rod 16 of signal 4. At the exit end of subsection 1 are the lead-wires 17 and 18, which include battery 19 and movable contacts 20 and 21.

22 is the armature of magnet-coil 12. When magnet-coil 12 is energized, armature 22 is attracted, so as to pick up circuit-controller 7 and lift it into the field of its magnet-coil 8 and close the circuit through magnet 5. Magnet-coil 8 has a relatively high resistance—say eight ohms—and magnet-coil 12 has a relatively low resistance—say one ohm.

In the normal condition of the circuits—that is, when there is no train in the block—signal 4 will be at "safety" and coil 8 will be included in the circuit of battery 19, so that the battery consumption will be reduced and merely sufficient to enable coil 8 to hold up the circuit-closer 7, as shown in the drawing. When a train enters subsection 1, it shunts coil 8, thereby opening at 7 the circuit through magnet 5 and causing signal 4 to go to "danger." The circuit-changer is thereupon shifted so as to exclude coil 8 from the track-circuit, but include coil 12 in the track-circuit. Coil 12 of course is not energized until the train has passed beyond the block or track-section guarded by signal 4. When the train has thus passed, coil 12 is energized, so as to attract the armature 22 and lift circuit-controller 7 to closed position, thereby causing signal 4 to return to "safety."

Coil 12 being of low resistance enables the

full strength of battery 19 to be utilized in closing circuit through magnet 5 at circuit-controller 7. In the movement of the signal 4 to "safety" the circuit-changer is shifted to its normal position, so as to include coil 8 in the track-circuit and exclude coil 12. Coil 8 being now energized maintains circuit-controller 7 in its hold-up or closed position and coil 12, being deenergized, drops its armature.

10 It is preferable that coil 12 be excluded from the track-circuit when coil 8 is included therein; but it would not be a departure from the invention to permit coil 12 to remain in the track-circuit with coil 8 when the signal 15 goes to "safety" instead of excluding coil 12 at this time.

11 It will be seen that when coil 12 is initially energized circuit - controller 7 is picked up and that when coil 8 is energized circuit-controller 7 is held up. It will also be seen that the energization of coil 8 initiates the movement of the circuit-changer (contacts 11 and 15) to the position in which coil 8 is included in the track-circuit. It will also be seen that the energization of coil 12 initiates the movement of signal 4 to clear position, the energization of coil 8 serving to maintain the signal in clear position. It will also be seen that when coil 8 is deenergized circuit-controller 7 drops from its held-up position to its pick-up position and that the deenergization of coil 8 initiates the movement of the signal to danger position and also initiates the movement of the circuit-changer to the position which excludes coil 8 from the track-circuit.

12 The track-relay at station B controls the signal 4 through the track-circuit of subsection 1 by means of the circuit-controllers 20 and 21, connected in this track-circuit, as heretofore described. 22 and 23 are the wires leading from the rails of subsection 2 to the track-relay. High-resistance magnet 24 is connected on one side to wire 22 and on its other side by wire 25 through moving contact 26 to wire 23. Low-resistance magnet 27 is connected by wire 28 to wire 23 and on its other side through wire 29, moving contact 30 and wire 31 to wire 22.

13 Magnet 24 is included in a local circuit which includes wire 31, battery 32, wire 33, circuit-controller 34, and wire 35. Circuit-controller 34 is operated by coil 27. Moving contacts 26 and 30 constitute the circuit-changer for the relay at station B and when attracted by coil 24 occupies the position shown in the drawing, at which time they include coil 24 in the track-circuit and exclude coil 27. When they are in the reverse position, they exclude coil 24 and include coil 27. The coils and contacts are shown in their normal position at station B. At this time contacts 20 and 21 are closed, thereby closing the track-circuit of subsection 1. Coil 24 is 65 energized and contacts 26 and 30, which con-

stitute the circuit-changer, are held up by coil 24. Coil 27 is deenergized and local circuit of battery 32 is open at circuit-controller 34. The track-circuit of the track-relay for station B includes the rails of subsection 2, battery 35, wire 36, circuit-controller 37, and wire 38. When coil 24 is deenergized, as by a train on subsection 2, contacts 26 and 30 move from their hold-up position into their pick-up position and track-circuit of subsection 1 is broken at contact 20. The change in the position of the circuit-changer excludes coil 24 and includes coil 27 therein, this latter circuit extending from wire 22, through wire 31, contact 30, wire 29, coil 27 to wire 23.

14 When current again flows through the track-circuit of subsection 2, coil 27 is energized, thereby closing at circuit-controller 34 the local circuit through battery 32 and coil 24. Coil 27 being of low resistance insures the utilization of ample current to reliably close circuit - controller 34. Current from battery 32 thereupon energizes coil 24, flowing from battery 32 through wire 33, circuit-controller 34, wire 35, coil 24, and wire 31 back to battery. Coil 24 lifts contacts 26 and 30 into their hold-up position and there holds them. This change in the position of contacts 26 and 30 excludes coil 27 and includes coil 24 in the track-circuit. It will be seen that the energization of coil 27 initiates the movement of the circuit-changer (contacts 26 and 30) from their pick-up position to their hold-up position, coil 27 working through the agency of the local circuit and coil 24 in effecting this result. When coil 27 is thus excluded from the track-circuit, it drops contacts 34 and 21, contact 34 breaking the local circuit of battery 32 and contact 21 closing the last break in the track-section of subsection 1. It will be seen that coils 24 and 27 bear the same relation to their track-circuit as do coils 8 and 12 to their track-circuit and that the two relays at stations A and B effect the same ultimate results, although in a different manner and by means somewhat different.

15 At station C the track-relay is shown in a second modified form. In this case the low-resistance coil 39 is connected on one side to wire 40, leading to one rail of subsection 3, and on its other side through wire 41, contact 42, wire 43 to wire 44, leading to the other rail of subsection 3. 45 is the battery of this track-circuit. High-resistance coil 46 is connected on one side to wire 44 and on its other side to wire 41. In this arrangement coils 39 and 46 are wound on the same core. When the parts are in their normal condition, as shown in the drawing, current flows through wire 40, low-resistance coil 39, high-resistance coil 46, and wire 44 through the track-rails and battery 45. The relay is energized and contact 42 is open and is held in its hold-up position by the relay, but more

particularly by the high-resistance coil 46 of the relay. When the relay is deenergized, as by a train entering subsection 3, contact 42 moves from its hold-up position to its pick-up position. This shunts high-resistance coil 46, thereby excluding it from the circuit and includes low-resistance coil 39 in the circuit. When the relay is thereafter energized, as by a train moving out of subsection 3, current flows first through low-resistance coil 39, so that this coil being energized moves the contact 42 from its pick-up to its hold-up position. This breaks the shunt around coil 46, so that both coils are thereupon included in the circuit and contact 42 is held in its hold-up position by both coils 39 and 46. Contact 42 constitutes the circuit-changer for this relay, doing the work of shifting the relay connection from one of low resistance to one of high-resistance just as do the circuit-changers at stations A and B. Relay at station C operates upon signal 4 through the agency of the track-circuits for subsections 1 and 2, the track-circuit of subsection 2 being operated through circuit-controller 37.

While I have shown my invention employed as a track-relay, it is to be observed that it may also be employed as a clearing-relay, where it will operate in the same way and possess the same advantages.

What I claim, and desire to secure by Letters Patent, is—

1. The combination of a circuit; with two magnet-coils, one of high resistance and one of low resistance; a circuit-changer connected with said circuit and so arranged that when in one position it excludes the high-resistance coil from said circuit but includes the low-resistance coil in said circuit; and when in its other position it includes the high-resistance coil in said circuit; and a circuit-controller arranged to be picked up when the low-resistance coil is initially energized and to be held up when the high-resistance coil is energized.

2. The combination of a circuit; with two magnet-coils, one of high resistance and one of low resistance; a circuit-changer connected with said circuit and so arranged that when in one position it excludes the high-resistance coil from said circuit but includes the low-resistance coil in said circuit; and when in its other position it includes the high-resistance coil in said circuit; and a circuit-controller arranged to be picked up when the low-resistance coil is initially energized and to be held up when the high-resistance coil is energized, the movement of said circuit-changer to its last-mentioned position being initiated by the energization of the low-resistance coil, and the movement of said circuit-changer to its first-mentioned position being initiated by the deenergization of the high-resistance coil.

3. The combination of a circuit; with two

magnet-coils, one of high resistance and one of low resistance; a circuit-changer connected with said circuit and so arranged that when in one position it excludes the high-resistance coil from said circuit but includes the low-resistance coil in said circuit; and when in its other position it includes the high-resistance coil in said circuit, and excludes the low-resistance coil from said circuit; and a circuit-controller arranged to be picked up when the low-resistance coil is energized and to be held up when the high-resistance coil is energized.

4. The combination of a circuit; with two magnet-coils, one of high resistance and one of low resistance; a circuit-changer connected with said circuit and so arranged that when in one position it excludes the high-resistance coil from said circuit but includes the low-resistance coil in said circuit; and when in its other position it includes the high-resistance coil in said circuit and excludes the low-resistance coil from said circuit; and a circuit-controller arranged to be picked up when the low-resistance coil is energized and to be held up when the high-resistance coil is energized, the movement of said circuit-changer to its last-mentioned position being initiated by the energization of the low-resistance coil, and the movement of said circuit-changer to its first-mentioned position being initiated by the deenergization of the high-resistance coil.

5. The combination of a track-circuit; with a signal; two magnet-coils one of high resistance and one of low resistance; the low-resistance coil, when first energized, initiating the movement of the signal to clear position, and the high-resistance coil when energized operating to maintain the signal in clear position; and a circuit-changer connected with said circuit and arranged to cut out the high-resistance coil after the latter has been deenergized and to cut in the high-resistance coil after the low-resistance coil has been energized.

6. The combination of a track-circuit; with a signal; two magnet-coils one of high resistance and one of low resistance; the low-resistance coil, when first energized, initiating the movement of the signal to clear position, and the high-resistance coil when energized operating to maintain the signal in clear position; and a circuit-changer connected with said circuit and arranged to cut in the low-resistance coil and to cut out the high-resistance coil after the latter has been deenergized and to cut out the low-resistance coil and to cut in the high-resistance coil after the low-resistance coil has been energized.

7. The combination of a track-circuit; with a signal; two magnet-coils, one of high resistance and one of low resistance; a circuit-controller arranged to be picked up by the coil of low resistance and held up by the

coil of high resistance; and a circuit-changer operated by the movement of the signal from one position to another, said circuit-changer acting when in one position to exclude the high-resistance coil and include the low-resistance coil in the circuit, and when in its other position acting to include said high-resistance coil in the circuit.

8. The combination of a track-circuit; with 10 a signal; two magnet-coils, one of high resistance and one of low resistance; a circuit-controller arranged to be picked up by the coil of low resistance and held up by the coil of high resistance; and a circuit-changer operated by 15 the movement of the signal from one position to another, said circuit-changer acting when in one position to exclude the high-resistance coil and include the low-resistance coil in the circuit, and when in its other position acting 20 to include said high-resistance coil in the circuit and exclude the low-resistance coil.

9. The combination of a circuit; with two magnet-coils, one of high resistance and one of low resistance; a circuit-changer connected with said circuit and so arranged that 25 when in one position it excludes the high-resistance coil from said circuit but includes the low-resistance coil in said circuit, and when in its other position it includes the high- 30 resistance coil in said circuit; a circuit-controller arranged to be held up by the high-resistance coil; and an armature for the low-resistance coil arranged to mechanically pick up said circuit-controller.

- 35 10. The combination of a circuit; with two magnet-coils, one of high resistance and one of low resistance; a circuit-changer connected with said circuit and so arranged that when in one position it excludes the high-resistance coil from said circuit but includes the low-resistance coil in said circuit; and when in its other position it includes the high-resistance coil in said circuit; a circuit-controller arranged to be held up by the high-resistance coil; and an armature for the low-resistance coil arranged to mechanically pick up said circuit-controller, the movement of 45 said circuit-changer to its last-mentioned position being initiated by the energization of the low-resistance coil, and the movement of 50 said circuit-changer to its first-mentioned position being initiated by the deenergization of the high-resistance coil.

- 55 11. The combination of a track-circuit including a source of energy; with a signal; two magnet-coils, one of high resistance and

one of low resistance; a circuit-controller arranged to be held up by the high-resistance coil; an armature for the low-resistance coil, arranged to mechanically pick up said circuit-controller; and a circuit-changer acting to change the connection of said coils with the track-circuit from one of high resistance when the signal is in clear position to one of low resistance when the signal is at danger. 60 65

12. The combination of a track-circuit including a source of energy; with a signal; two magnet-coils, one of high resistance and one of low resistance; a circuit-controller arranged to be held up by the high-resistance coil; an armature for the low-resistance coil arranged to mechanically pick up said circuit-controller; and a circuit-changer operated by the signal and acting to change the connection of said coils with the track-circuit 70 75 from one of high resistance when the signal is in clear position to one of low resistance when the signal is at danger.

13. The combination of a track-circuit including a source of energy; with a signal; 80 two magnet-coils, one of high resistance and one of low resistance; a circuit-controller arranged to be held up by the high-resistance coil; an armature for the low-resistance coil arranged to mechanically pick up said circuit-controller; and a circuit-changer acting to include the high-resistance coil when the signal is in clear position and acting to exclude the high-resistance coil and include the low-resistance coil in the circuit when the signal is 85 90 at danger.

14. The combination of a track-circuit including a source of energy; with a signal; two magnet-coils, one of high resistance and one of low resistance; a circuit-controller arranged to be held up by the high-resistance coil; an armature for the low-resistance coil arranged to mechanically pick up said circuit-controller; and a circuit-changer operated by the signal and acting to include the high-resistance coil when the signal is in clear position and acting to exclude the high-resistance coil and include the low-resistance coil in the circuit when the signal is at danger. 95 100

In testimony whereof I have signed my name to this specification in the presence of two subscribing witnesses.
